FORM FOR CASTING BLOCKS

Arthur E. Troiel, Berkeley, Calif.

Application November 9, 1942, Serial No. 464,987

2 Claims. (Cl. 25—121)

This invention relates to forms for casting blocks and particularly to forms for casting a plurality of cubical or rectangular objects of identical dimensions. Cubical or rectangular blocks of concrete or other similar material capable of being cast in forms are useful in many purposes such as foundation stones or building blocks, and recently blocks of heavy aggregate concrete have come into use as ballast blocks for trimming or balancing large ships. Blocks of this kind should be uniform in shape and dimensions and the forms in which they are cast should be sufficiently durable to permit them to be used an indefinite number of times, but should be inexpensive in construction, light to handle and easy to strip from the cast blocks after they have set.

It is the object of the present invention to provide forms having all of the requisites above mentioned and to provide forms for casting cubes or similar shapes efficiently and inexpensively and for casting them in tiers or groups which are capable of being easily handled and transported by appropriate machinery.

One form of the present invention is illustrated in the accompanying drawing and described in detail in the following specification wherein reference is made to the drawing.

In the drawing:

Fig. 1 is a perspective view of one end of a set of forms embodying the present invention and illustrated as set up for pouring on blocks previously cast in the same set of forms;

Fig. 2 is a side elevation of one of the longitudinal form plates included in the set shown in Fig. 1; and

Fig. 3 is a side elevation of one of the transverse form plates shown in Fig. 1.

The set of forms illustrated in the drawing is designed for casting a group of cubical blocks, the group being three blocks wide and six blocks long. While this is sufficient to illustrate the structure of the forms and the principles of the invention, it should be understood that any number of blocks may be cast at once depending upon their size and upon convenience in handling the forms. As to convenience in handling, it has been found that in casting 10½ inch cubical ballast blocks, forms accommodating three blocks in their width and 11 in their length, or 33 blocks in all, are of a convenient size to be efficiently set up and stripped by no more than two men working without mechanical lifting equipment.

As illustrated in the drawing, the forms consist of vertically disposed longitudinal form

plates 10, the details of construction of which are shown in Fig. 2, and transverse form plates 11, one of which is illustrated in Fig. 3. Both types of plates are formed of heavy gage sheet metal or equivalent material. The longitudinal plates 10 and the two end plates 11 are wider than the remainder of the transverse plates 11 so that they extend downwardly a couple of inches, the lower edges of the intermediate longitudinal plates being retained in the grooves by the blocks previously cast, and the end plates and side plates overlapping the outer surfaces of these blocks to retain the whole form in position. The lengths of all the plates depend, of course, upon the number of blocks to be cast. The longitudinal plates 10 are provided with a plurality of spaced vertical slots 13 extending from their top edges downwardly toward their bottom edges and spaced apart a distance determined by the dimensions of the blocks to be cast. The transverse plates 11 are provided with similar slots indicated at 14 which extend from their bottom edges upwardly. By registering the slots in the two types of plates, they may be assembled in the position illustrated in Fig. 1 and there interlocked to form cubical reticules which serve as forms for the casting of individual blocks.

Each end of every plate is provided with flanges such as indicated at 15 which serve to back up and support the outermost plates when they are assembled, and retain the plates against bulging outwardly due to the weight of the concrete which is cast in the forms. In most instances the flanges 15 are preferably formed on channel-like members 16 which slide over the outer ends of the plate and project beyond the outer walls of the assembled form and which are riveted, welded, or otherwise securely fixed thereon. However, on the outermost longitudinal plates 10, the flanges 15 are formed as one part of right angular members 17 as in this case the double flange is unnecessary. The channel-like members 16 and the angular members 17 are somewhat lighter in construction than they appear in the drawing where their thickness is exaggerated. In practice they are preferably formed by bending metal of substantially the same gage as the metal of which the forms are made. In every case the ends of the plates are provided with perforations which extend through the channel members 16 or angle members 17, such perforations being indicated at 18 in the drawing. These perforations provide a convenient purchase for a hook or other implement which may be used in handling the forms and particu-

larly in stripping them after the concrete is set, this stripping being accomplished by sliding the forms upwardly.

In use, the forms are first set up over wooden planks such as indicated at 19 or other suitable foundation members and are filled with concrete which is screeded flush with the top edges of the forms. The planks 19 in this instance serve as the bottoms of the forms. When this first level of blocks has set sufficiently to permit removal of the forms, the transverse form members 11 are removed. This is accomplished by raising them upwardly, and as all of the forms are preferably sprayed with a lubricant before they are poured and have smooth planar surfaces, they may be withdrawn from their position between the blocks without difficulty. After the form members 11 have been stripped, the outermost of the longer members 10 which are then free are set aside and the inner members 10 are stripped upwardly but not entirely clear of the blocks previously cast between them. The height of the longitudinal form members is somewhat greater than the height of the blocks to be cast, as indicated in Fig. 1 where the dotted line 20 shows the position of the top of a set of blocks over which the forms are being assembled. Thus when the central members 10 are raised to the proper height for assembling the forms, a couple of inches of their lower edges are still retained in the spaces 21 between the blocks. In order to retain all of the members 10 at this elevation, they are slotted, as indicated at 22 in Fig. 2, from their bottom edges upwardly to receive an elongated pin 23 which extends through the slots and which rests on the top surface of the set of blocks previously cast. The pins 23 extend across all of the blocks and through registering slots 22 in all of the plates 10. With the longitudinal form plates 10 supported in this manner, the intermediate transverse plates 11 are assembled in place with their lower edges supported just above the spaces 21 which extend transversely of the set of blocks, while the end-most transverse plates which are wider extend downwardly to overlap the previously cast blocks. The lower edges of all of the longitudinal form plates and the two end transverse plates are thus firmly held by the blocks previously cast. The blocks serve as the bottoms for the forms. It is preferable to place a layer of building paper or similar material on the bottoms of the forms so that in casting a set of blocks, they will not adhere to the blocks previously cast. This paper is placed over the pins 23 so that when the new batch of concrete is poured it does not embrace the pin which is protected by the paper, but leaves it free to be withdrawn and replaced at a higher elevation when the forms are again stripped.

With forms constructed in the manner above described, they may be stripped and replaced at a higher elevation as many times as desired, convenience usually limiting the height of the pile 5 of blocks so cast to 4 or 5 blocks. The entire pile of blocks after being cast constitutes a unit which may be conveniently handled for transportation. Underlying the planks 19 upon which the first layer of blocks is cast are transverse 10 planks such as indicated at 24 which rest upon foundation timbers 25. With this arrangement a conventional lumber carrier which is a motor vehicle with a chassis comprising high spaced frames so that it may be driven over a pile of 15 lumber or the like to straddle the same, may be employed to transport the entire pile, as it may be driven over the pile and is capable of lifting the same for transportation by means of the projecting ends of the planks 24. The forms are 20 easily stripped from between the blocks after the concrete is set by reason of the perforations 18 which provide a purchase for one end of a hook, not shown, the other end of which may be connected with a lever, which, fulcrumed on a wooden 25 block resting on top of the concrete casting gives sufficient leverage to overcome the friction and draw the form plates upwardly. The spaces 21 between the blocks serve to support and retain the form plates in their proper positions as they 30 are moved progressively upwardly in casting successive layers of blocks.

Having thus described my invention, what I claim and desire to secure by Letters Patent is:

1. Forms for casting blocks comprising longitudinal and transverse vertical plates arranged to provide a plurality of reticules into which concrete may be poured, said longitudinal plates and the transverse plates at the ends of the forms only extending downwardly beyond the bottom 35 of the casting space, whereby upon upward stripping of the forms their downwardly extending edges will embrace the blocks cast to support the forms for casting a second layer.

2. Forms for casting blocks comprising longitudinal and transverse vertical plates arranged to provide a plurality of reticules into which concrete may be poured, said longitudinal plates and the transverse plates at the ends of the forms only extending downwardly beyond the bottom 40 of the casting space, whereby upon upward stripping of the forms their downwardly extending edges will embrace the blocks cast to support the forms for casting a second layer, the downwardly extending portions of the longitudinal plates being slotted upwardly to receive supporting pins 45 which rest on the previously cast blocks.

ARTHUR E. TROIEL.
